Fig. 2.

To all whom it may concern:

Be it known that I, Irol G. Gangbin, a citizen of the United States, residing at Armona, in the county of Kings and State of California, have invented a new, original, and ornamental Design for Compartmented Dish, for which the following is a specification, reference being had to the accompanying drawing, forming a part hereof, and in which:

Fig. 1 is a perspective view of a compartmented dish showing my new design; a dial indicator being shown in broken lines; and

Fig. 2 is a top plan view thereof with the dial indicator member omitted for convenience of illustration.

I claim:

The ornamental design for a compartmented dish, as shown and described.
